UNITED STATES PATENT OFFICE.

GURDON W. HULL, OF WALLINGFORD, CONNECTICUT, ASSIGNOR TO
SIMPSON, HALL, MILLER & CO., OF SAME PLACE.

DESIGN FOR A SPOON OR FORK HANDLE.

SPECIFICATION forming part of Design No. 15,617, dated December 16, 1884.

Application filed August 9, 1884. Term of patent 14 years.

To all whom it may concern:

Be it known that I, GURDON W. HULL, of Wallingford, in the county of New Haven and State of Connecticut, have invented a new Design for Spoon or Fork Handles; and I do hereby declare the following, when taken in connection with accompanying drawing, and the letters of reference marked thereon, to be a full, clear, and exact description of the same, and which said drawing constitutes part of this specification, and represents a face view of a spoon, broken lines indicating the termination when made in shape of a fork, such termination, however, not constituting any portion of this invention.

This design relates to the ornamentation of the handles of spoons, forks, and like articles of table-service; and it consists in the ornamentation, as hereinafter described, and shown in the accompanying illustration. At about midway of the length of the handle is a boss, *a*. From the boss the handle gradually expands to the tip. The surface is bordered by a

bead. Transversely across the face are two ornamental bands, *b c*, leaving a plain space, *d*, between them. On the surface between the boss *a* and the transverse band *b* the surface is reeded, the reeds gradually expanding in width from the boss to the band *b*. From the band *c* to the tip the surface is also reeded, as shown in the accompanying illustration. The boss *a* may be omitted entirely, or some other ornament inserted in place of it, this constituting no part of the present design.

I claim—

The herein-described design for the ornamentation of the handles of spoons and forks, consisting in the transverse bands *b c* across the face of the handle, the surface below the band *b* and above the band *c* reeded, as shown in the accompanying illustration.

GURDON W. HULL.
